[57] **CLAIM**

The ornamental design for a morning sun textured door design with nesting profile, as shown and described.

DESCRIPTION

FIG. 1 is a front elevational view the back being a mirror image thereof of a morning sun textured door design with nesting profile showing my new design;

FIG. 2 is an enlarged fragmentary front view of a portion of the Morning sun textured door design with nesting profile as shown in FIG. 1;

FIG. 3 is a top view the bottom being a mirror image thereof; FIG. 4 is a cross sectional view through lines 4—4 of FIG. 1 revealing the details of the concave and convex curves in the face of the morning sun textured door design with nesting profile; and,

FIG. 5 is an enlarged view of the molding located on the center, right side of the article in FIG. 4.

The characteristic feature of the design resides in the unique frame design appearing in FIG. 1 at the outside edges of the upper, arched frame, best shown in detail in FIG. 2; and the profile of the concave and convex curves in the panel frame members in the face of the morning sun textured door design with nesting profile.
